UNITED STATES PATENT OFFICE

DANA E. HARDING, OF MELROSE, MASSACHUSETTS, ASSIGNOR TO HARDING ENGINEERING COMPANY, OF EAST BOSTON, MASSACHUSETTS, A CORPORATION OF MASSACHUSETTS

CHEEKING MACHINE

Application filed August 31, 1928. Serial No. 303,300.

My present invention relates to the manufacture of leather from hides or skins, and more particularly to an improved apparatus for removing surplus material from the 5 cheeks or butts of such hides or skins.

An important step in the manufacture of leather from hides and skins is the operation of removing superfluous flesh, and a portion of the hide or skin from the cheeks 10 or other portions of the hide where the material is naturally thicker than at other portions. So difficult is it to perform this operation satisfactorily that in a great many tanneries the cheeked portions are cut off and 15 go into the scrap pile. As each portion cut off reduces the superficial area of the resulting leather, various machines have been devised for saving such cheeked portions if possible, and none of them, as far as I am aware 20 have been successful. As the cost of leather is continually mounting, the production of scrap from what should be merchantable leather is an economic waste that all tanneries are striving to eliminate.

25 In my present invention I have devised an improved machine for skiving off superfluous flesh and hide from the cheek or other portions of such hide, and such work is performed mechanically and with the resulting 30 increase in the merchantable leather produced.

35 Heretofore it has been attempted to perform this cheeking operation manually, that is, the operator has been obliged to hold the hide or skin against the tension exerted thereon by the skiving knife or cutter and the work has been so laborious that where the process is continued, the operators cannot 40 work but for a few hours a day and are soon incapacitated for further work and the disabling of the operators has been so pronounced that in the majority of tanneries at the present day, such manual cheeking of 45 hides or skins has been dispensed with even though it is realized that the operation is an exceedingly important one from an economic standpoint.

In carrying out my invention, I provide 50 a holding device which positively holds a hide or skin at a plurality of points simul-

taneously and mechanically opposes the tension of the cutting knife or skiver and in actual practice, an operator may run the machine without undue fatigue continuously for the usual working period day in and day out. 55

The object of my invention, therefore, is an improved cheeking machine for cheeking hides or skins.

In the accompanying drawings illustrating a preferred embodiment of my invention, 60

Fig. 1 is a front elevation;

Fig. 2 is an end elevation;

Fig. 3 is an enlarged end elevation of a portion of the left-hand end of Fig. 1; 65

Fig. 4 is a sectional view on the line 4—4 of Fig. 1;

Fig. 5 is an enlarged sectional view on the line 5—5 of Fig. 1;

Fig. 6 is an enlarged view of Fig. 4 with certain parts removed for clearness of illustration; 70

Figs. 7, 8, and 9 are sectional views showing the mechanism in the upper part of Fig. 4 and each in a different position of operation; 75

Fig. 10 is an enlarged sectional view of the clamping apparatus;

Fig. 11 is an enlarged view of the upper left-hand portion of Fig. 1 with certain parts broken away for clearness of illustration; 80

Fig. 12 is a sectional view on the line 12—12 of Fig. 11;

Fig. 13 is a section on the line 13—13 of Fig. 2;

Fig. 14 is a detail view partly in section of one of the removing roll operating arms;

Fig. 15 is a section on the line 15—15 of Fig. 4;

Fig. 16 is an elevation of the end of the 90 clamping arm;

Fig. 17 is a detail showing the arrangement of the "fanning out" device;

Fig. 18 is a partial plan view of Fig. 17, 95 and

Fig. 19 is a side elevation of Fig. 17.

Referring to the drawings, 10 and 11 designate side frame members arranged parallel with and spaced apart from each other and held in rigid and spaced relation by cross 100

bars 12 and 13 respectively, such bars being secured to the members 10 and 11 by bolts 14. Secured to the top of the end frame member 10 by bolts 15 is a member 16, while 5 secured to the top of the end frame member 11 by bolts 17 is a member 18. The members 16 and 18 are arranged parallel to each other and in each of said members is formed a bearing or bearings, being in alinement with 10 each other and rotatably mounted in said bearings is a shaft 19. Secured to the outer face of the frame member 11 by bolts 20 is an outboard bearing member 21, in which is formed a bearing 22 in alinement with the 15 bearings above referred to as being in the members 16 and 18 and such bearing 22 supports the outer end of the shaft 19. Formed in the end frame members 10 and 11 are bearings that are in alinement with each 20 other and in alinement also with a bearing 23 formed in the outboard bearing member 21, and in such bearings is rotatably mounted a power shaft 24, and on such power shaft is fixed a tight pulley 25 and a loose pulley 26, 25 and over which pulleys may run a belt leading from a suitable source of power. Slidably mounted in the outboard frame 21 is a belt shifting device 27 and by means of which the belt referred to may be shifted from the 30 loose pulley 26 onto the tight pulley 25. Secured to a boss 28 formed on the outboard bearing bracket 21 is a stub shaft 29. Rotatably mounted on the stub shaft 29 is a gear 30 and pinion 31, such gear and pinion being 35 secured together so as to rotate as a unit. The gear 30 meshes with and is driven by a pinion 32 secured to the power shaft 24. The pinion 31 meshes with and drives a gear 33 formed on a clutch hub 34 that is rotatably 40 mounted on the shaft 19. Rotatable with but slidable on the shaft 19 and associated with the clutch hub 34 is a clutch sleeve 35, and further description and operation of the clutch mechanism will be made hereinafter. 45 It is sufficient to say that the shaft 19 may be rotated at will from the shaft 24 by means of the clutch members 34 and 35. Secured to the shaft 19 between the members 16 and 18 is a segmental member 36 provided with 50 a radially extending face plate 37, on which is secured a corrugated member 38, the corrugations extending parallel to the shaft 19. Also formed on the corrugated member 38 is an apron 39 which extends over and 55 protects the shaft 19, as will be clearly seen from an inspection of Fig. 4 or 6. Secured to the shaft 19 and at either end of the segmental member 36 is a member 40, each of these members being drilled at their ends 60 to receive shafts 41, the shafts 41 being in alinement with each other. Pivots mounted on each of the shafts 41 is a link 42, each of such links being provided with a laterally projecting member 43, drilled to 65 receive as a sliding fit the upper threaded

end of a bolt 44, such bolt being adjustably secured to the member 40 by nut 45. Threaded on the end of the bolt 44 is a nut 46 and by means of which the amount of movement of the links 42 about the shafts 41 may be 70 adjusted. Pivots attached to the other end of each of the links 42 on pivot shaft 47, is one end of a lever 48. The lever 48 is pivots attached at its other end to one end 75 of a link 49. The links 49 are each pivots attached at their other end to a bell crank lever 50. One arm of the bell crank lever 50 is pivots attached at 51 to the end face of the segmental member 36, while the other arm is provided with a cam roller 52 for a 80 purpose to be hereinafter described. The manner in which the levers 48 and 49 are pivots attached together is clearly shown in Fig. 16, and referring to Fig. 16, it will be noted that the link 49 has a cylindrical projection 53 thereon and on which is slidably mounted a boss 54. The outer end of the cylindrical member 53 is threaded to receive an adjusting nut 55 and between the adjusting nut 55 and the boss 54 on the cylindrical 85 member 53 is a helical spring 56. It will be obvious, therefore, that the boss 54 is yieldingly mounted on the member 49. Laterally extending from the boss 54 is a cylindrical shaft 57 on which is pivots mounted the 90 link 48. The cylindrical shaft 57 extends laterally beyond the link 48 and inwardly of the machine. As there are two sets of links 48 and 49, and, therefore, two cylindrical shafts 57, it is arranged that such shafts 95 57 are in alinement with each other and on such shafts is pivots mounted a clamp bar 58, such clamp bar being provided on its lower end or its lower edge 59 with corrugations that co-operate with the corrugations 100 in the member 38 that is attached to the segment 36. The clamp bar 58 is, therefore, yieldingly held in position and the tension which such clamp bar 58 exerts on the hides or skins 59a, when the same are in position on the segment 36, may be adjusted by means of the adjusting nuts 55. Mounted on the side frame members 10 and 11 and secured thereto by bolts 60, are frames 61 and 62 respectively, and on the opposing faces of the frames 115 61 and 62 are secured cam members 63 and with which cams the cam rollers 52 on the bell crank levers 50 engage, as will be hereinafter described. On the frames 61 and 62 are formed extensions 64 and 65 respectively 120 and in each of these extensions is mounted a stub shaft 66. On the stub shafts 66 is pivots attached a release lever 67 provided at its outer or free end with a latch 68 that engages with the clamp bar 58. Formed integral with each of the levers 67 is an arm 69 provided at its outer end with a knob 70, which knob extends upwardly and is located adjacent to the front top portion of the machine. On each of the members 69 is secured 125

a piston 71 which works in the cylinder 72 secured to the extensions 64 and 65 and in such cylinders is arranged a spring 73 and which tends to rotate the release lever 67 about the stub shaft 66, but which will allow limited clockwise direction of such lever. In the normal or inoperative position of the device, the links 48 and 49, as well as the bell crank lever 50, occupy the position shown 10 in Fig. 4 and with the clamp bar 58 in the position shown therein, this mechanism being held in inoperative position by the latches 68 on the release lever 67 engaging with the clamp bar 58. The links 48, 49, and bell 15 crank lever 50, together with the links 42, constitute a clamping mechanism, the function and operation of which will be herein-after described. It is to be noted, however, that the weight of the clamp bar 58 is sufficient, when such clamp bar is released by depressing the knob 70, to throw the clamping mechanism 48, 49, 50, and 42 from the position shown in Figs. 4 and 6, to the position shown in Fig. 7, where it will be seen that 20 the corrugations on the portion 59 of the clamp bar 58 has moved into operative relation with the corrugations on the member 36 carried by the segment 36, thus clamping a hide or skin 59a in position to be operated 25 upon. In each of the extensions 64 and 65 is secured a shaft 74, which extends parallel to the shaft 19 above described, and on such shaft adjacent to each of the extensions 64 and 65 is pivotally mounted a member 75, 30 and such members 75 are joined together at their free ends by a transverse member 76, such member 76 being provided intermediate its ends and on the top edge thereof with a handle 77. Secured to the extensions 35 40 and 65 by bolts 78 is a cross bar or brace 79. The cross bar or member 79 is provided with a lateral extension 80, through which passes a threaded member 81 which screws into the cross bar 79 and holds the frame structure, composed of the members 75 and 45 76, against rotary movement on the shaft 74, but which may be readily placed in condition for rotary movement by backing off the member 81 and swinging the same on its 50 pivot away from the element 80. Pivotally mounted on the shaft 74 and parallelly arranged with respect to each other are rearwardly and downwardly extending arms 82. The lower ends of such arms 82 extend downwardly and forwardly, as shown in Fig. 4, 55 and at their lower ends are provided with lateral extensions 83 and a pivot shaft 84. Through each of the lateral extensions 83 is threaded an adjusting screw 85, while pivotally mounted on the pivot shaft 84 is a "fanning out" element 86, the outer surface of which is provided with a plurality of 60 parallelly arranged corrugations 87 and the inner face is adapted to be engaged by the 65 adjusting screws 85 above referred to.

Referring to Fig. 17, it will be noted that if the dot and dash line designated by 88, represents the medial line of the machine or the line corresponding to 4-4 of Fig. 1, that the corrugations 87 on the left side of such dot and dash line 88, make an angle with the line 88 in a certain direction, while the corrugations 87 on the members 86 to the right of the line 88 also make an angle with the line 88 but in the opposite direction. The members 86 are adapted to engage with the segment 36 with the corrugations thereon 87 in actual engagement with the hide or skin 59a carried by such segment 36 and the arrangement of corrugations 87 is such that the hide or skin 59a will be "fanned out" from a center line just prior to the engagement with the hide of a cutting device to be herein-after described. To each of the arms 82 is pivotally attached a rod 89, such rod being threaded at its end and with the threaded end passing through a perforation in the cross member 76, such threaded end being provided with adjusting nuts 90. Between the inner face of the cross members 76, and the lower end of the rods 89 is a coil spring 91 and which urges the arms 82 about the shaft 74 in a counter-clockwise direction to force the members 86 into engagement with the hide or skin 59a that may be on the segment 36 and the tension of the spring 91 is adjusted by means of the adjusting nuts 90.

On each of the side frame members 10 and 11 is formed bearings 92 and 93 respectively and secured in such bearings is a shaft 94. Rotatably mounted on the shaft 94 is a frame 95. Secured to the upper surface of the end frame members 10 and 11 by bolts 96 and extending between such end frame members is a cross bar 97. Formed on the cross bar 97 are bearings 98 and in these bearings 98 is rotatably mounted a shaft 99 provided with an eccentric 100. Associated with the eccentric 100 is a split bearing 101 forming virtually an eccentric strap and this split bearing 101 is slidably mounted in a slideway 102 formed in the frame 95. Secured to one end of the shaft 99 is an arm 103 and by means of which the shaft 99 may be rotated and, therefore, the upper end of the frame 95 moves inward or outward toward or from the segment 36, as will be clearly obvious from an inspection of Fig. 4. Secured to the outer face of the end frame member 10 by bolts 104 is a graduated disc 105 and with which an indicator 106 on the arm 103 co-operates to determine the amount of inward or outward movement of the frame 95 with respect to the segment 36. Secured to the upper face of the frame 95 so as to lie parallel to the segment 36 is a cutter 107, the cutting edge of the cutter extending transversely to the direction of movement of a hide or skin 59a that may be carried by the segment 36. This cutter is adjustably mounted by means of the bolts 108 and, as 110

above described, may be adjusted toward and from the segment 36.

Formed on the same member as the graduated disc 105 is a member 109 drilled to 5 receive as a sliding fit a plunger 110, which plunger has a reduced portion 111 which extends downwardly through a perforation in the member 109. The lower end of the reduced portion 111 is threaded to receive 10 adjusting nuts 112 which are, therefore, located outside of the member 109. Within the member 109 and surrounding the reduced portion 111 is a coil spring 113 which tends to force the plunger 110 upwardly, as viewed 15 for example in Fig. 2, and the tension of the spring 113 is regulated by the adjusting nuts 112. Pivoted attached on a shaft 114 in the member 109 is a latch lever 109a, one end 115 of which is provided with a laterally 20 extending shaft 116 which extends into a hole 117 bored in the member 109 between the bottom of the hole 117 and the outer end of the transverse shaft 116 is a spring 118 which urges the shaft 116 outwardly, as viewed in 25 Fig. 2, and tends to rotate the latch lever about the shaft 114 in a counter-clockwise direction. The other end 119 of the latch lever has formed thereon a latch 120 which is arranged above the upper end of the plunger 110 and spaced apart therefrom. Secured to 30 the outer end of the shaft 19 adjacent to the end frame member 10 is a member 121 slotted, as indicated at 122, and extending across such slot is a shaft 123. Rotatably mounted 35 on the shaft 123 in the slot 122 is a latch 124, the outer end of which engages with both the latch 120 and the upper end of the plunger 110. On this latch 120 is formed an arcuate cam member 125 which lies in the path 40 of movement of a roller 126 mounted on one arm of a bell crank lever 127 that is rotatably mounted on a shaft 128 secured to the frame of the machine. The other arm of the bell crank lever 127 has rotatably mounted there- 45 in a roller 129 which lies in the path of movement of a lug 130 carried by the lever 48 adjacent to the end frame member 10. Yielding means (not shown) is provided for the purpose of rotating the latch lever 124 back 50 into its initial position after the cam surface 125 thereon has been disengaged by the roller 126. On the inner face of the lever 48 adjacent the end frame member 11, is a lug 131 which is adapted to engage in the downward 55 movement of such lever 48 with the end portion 132 of an arm 133 pivotally mounted on the shaft 134 secured to the side frame member 11. The arm 133 is perforated adjacent the shaft 134 with a vertical hole through 60 which passes the lower threaded end of a lever 135, such lower threaded end being provided with adjusting nuts 136 and with a coil spring 137 which lies between the adjusting nuts 136 and the lever 135, this connection 65 providing a yielding connection between the

arm 133 and the lever 135. The upper end of the lever 135 is pivotally attached to one arm of a bell crank lever 138, which is rotatably mounted on a shaft 139 secured to lugs 140 formed on the frame member 62. The 70 other arm of the bell crank lever 138 is forked to partially encircle a portion of the sleeve 139 on which is formed one of the clutch members 35, and such forked ends are provided with inwardly extending pins 140a 75 which extend into and engage in an annular groove 141 in such sleeve 139. When the clamp bar 58 is released by depressing the knobs 70, the weight thereof, as above explained, is sufficient to cause a pivotal movement of the levers 48 and 49 and the lug 131 on one of the levers 48 engages with the end 132 of the pivoted arm 133, forcing such pivoted arm downward and causing a rotative movement thereof, together with the shaft 80 134, in a clockwise direction, this movement causing a downward movement of the lever 135, thus rotating the bell crank lever 138 about the shaft 139 and causing a sliding movement of the sleeve 139 on the shaft 19, 85 thus bringing the clutch member 35 into engagement with the clutch member 34 on the hub of the gear 33. Secured to one end of the shaft 134 is a member 142 which has formed integral therewith an arcuate arm 143 90 and a radially extending arm 144, as clearly shown in Figs. 11 and 12. Formed on the sleeve 139 is a cam 145 with which the radially extending arm 144 is adapted to engage, and also formed on the sleeve 139 is a cam 146, 95 with which the arcuate arm 143 is adapted to engage. When the shaft 134 is rotated by the arm 133 in the direction of the arrow shown in Figs. 5 and 12, the outer end of the arm 143 is moved downwardly out of engagement of the cam 146 and the arm 144 is moved into position to engage with the cam 145. The removal of the outer end of the arm 143 from the cam 146 takes place simultaneously with the movement to the left of the 100 forked arm of the bell crank lever 138 to thus bring the clutching members 34 and 35 into engagement with each other. As the lug 131 on the lever 138 engages the portion 132 of the arm 133, there is immediately a rotative movement of the shaft 134 and immediately thereafter the connecting together of the clutching elements 34 and 35. This causes a rotative movement of the shaft 19 which carries the lug 134 off the portion 132 of the 105 arm 133, and beyond such arm. As the shaft 19 rotates the cam 145 thereon, engaging with the outer end of the radially extending arm 144, rotates the shaft 134 and the outer end of the arm 143 engaging with the cam 146 110 will force the sleeve 139 to the right, as shown in Fig. 11, so that when the shaft 19 has completed a single full revolution, the clutching members 34 and 35 will be brought out of 115 engagement with each other. As at this 120 120 connection

time—that is, when the shaft 19 completes its full revolution—the latch 124 is riding onto the latching face 120 of the latch lever 119 and such latch 124, being in its initial 5 position with respect to the member 121, will strike the plunger 110 and the latch face 120 will move into position to lock the latch 124 in the position shown in Fig. 2 and all parts of the device are again brought to rest.

10 Attached to the side frame members and extending therebetween, adjacent the front of the machine, is an apron 147, while adjacent the upper end of the frame 95 is an apron 148.

15 Rotatably mounted in the end frame members 10 and 11 and arranged parallel to the power shaft 24 is a shaft 149, on which is secured an elongated, preferably rubber, removing roll 150. Secured to said shaft 149 adjacent the end frame member 11, is a gear 151 which meshes with and is driven by a gear 152 rotatably mounted on a shaft 153 rotatably mounted in the end frame members. The shaft 153 meshes with and is driven by a gear 20 154 which is rotatably mounted on a shaft 155 rotatably mounted in the end frame members 11. The gear 154 meshes with a pinion 156 rotatably mounted on a stub shaft 157 secured to the end frame member 11. The pinion 156 25 meshes with and is driven by a gear 158 secured to the power shaft 24. The train of gears above described rotates the shaft 149 and, therefore, the rubber removing roll 150 moves in the direction of the arrow shown in Fig. 5.

30 On the inner face of each of the end frame members 10 and 11 are arranged stub shafts 159 and on each of these stub shafts is rotatably mounted a roll 160. The stub shafts 159 are arranged on the circumference of a circle 35 of which the shaft 155 is the center and on each pair of rolls 160 is mounted an arcuate slotted member 161, which, therefore, is movable in a circumference of which the shaft 155 is the center. Extending between the arcuate 40 members 161 and rotatably mounted therein is a shaft 162 on which is secured, adjacent to one end, a pinion 163 that meshes with and is driven by the gear 154 in the direction of the arrow shown in Fig. 5 and on this shaft 162 45 also is secured a removing roll, preferably of rubber, 164. On each end of the shaft 162 is provided a sleeve 165 and engaging with each sleeve 165 is an arm 166, as clearly shown in Fig. 15. The arms 166 extend forwardly of the machine, as viewed in Fig. 4, and by reference to Fig. 14, it will be seen that each arm 166 is counterbored at 167 and slotted at 168, while the outer end of the counterbored portion is threaded as indicated at 169 and provided with the clamping means indicated by the numeral 170. Extending into and through the counterbored portion 167 is a threaded member 171, having as an integral part thereof a further extending threaded 50 member 172 which extends into the slot 168 and is provided therein with a nut 173. Slidably mounted on the member 171 is an externally threaded sleeve 174 which screws into the threaded portion 169 of the arm 166, and threaded on the portion 171 is an adjusting nut 175. Between the adjusting nut 175 and the threaded sleeve 174 is a coil spring 176 which continually urges the member 177 into the counterbored portion 167, or to the left as viewed in Fig. 14. Formed on the outer 55 end of the member 171 is a boss 177 provided with a transversely arranged hole 178 therein. Rotatably mounted in the end frame members 10 and 11 and parallel to the power shaft 24 is a cam shaft 139 and at each end of such cam shaft are secured two cams, 180 and 181 respectively. There are thus four cams on the cam shaft 139, two of such cams, one at each end, being similarly placed and also the other two cams, one at each end, while differently 60 placed with respect to the first pair, are similarly placed with respect to each other, for a purpose to be hereinafter described. Secured to the cam shaft 139 is a pinion 182 which meshes with and is driven by a gear 183 secured to the power shaft 24. Secured to each of the end frame members 10 and 11 in alignment with each other and parallel to the cam shaft 139, are stub shafts 184 and on each of such shafts is rotatably mounted a bell crank lever 65 60 provided with a long arm 185 and a short arm 186. Rotatably mounted in the end of the short arm 186 of each of the bell crank levers is a cam roller 187 which engages with a cam 181 on the cam shaft 139. Intermediate the ends of the long arm 185 is rotatably mounted a cam roll 188 which engages with the cam 180 on the cam shaft 139. The lower end of each of the long arms 185 of the bell crank lever is forked, as clearly shown in Fig. 1, and in each of such forked ends is mounted a shaft 189, which shaft 189 passes through the hole 178 in the end 70 75 80 85 90 95 100 105 110 115 120 125 130 135 140 145 150 155 160 165 170 175 180 185 188 190 195 198 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

As has been above described, the releasing of the clamp bar 58 causes a rotative movement of the levers 48 and 49 and associated links about their pivot points so as to bring the roll 52 into the position shown, for example, in Fig. 7. That is, such roll will be below the point 190 of the cams 63. The levers 48, 49, bell crank lever 50, and link 42, act as a clamping device which is locked when the shaft 19 rotates in the direction of the arrow shown in Figs. 4 and 6, 7, 8 and 9, for example, thus holding the corrugated portion 59 of the clamping bar 58 in close association with the corrugated member 38 on the face 37 of the segment 36, thus holding the hide or skin 59a firmly in position. As the segment 36 rotates when the clutching members 34 and 35 engage each other a complete revolution, mechanism has been provided for releasing the clamping device above described and forcing the clamping bar 58 out of engagement with the segment 36. Such mechanism is as follows.

On the inner face of each of the frame members 16 and 18 is arranged a cam plate 192. On each of the levers 48 is arranged a lug 193. The cams 192 and lugs 193 are adapted to engage with each other during the rotative movement of the segment 36 and parts carried thereby and it will be obvious from an inspection of Fig. 9 that such cam and lug are in engagement with each other, thus forcing the lever 48 about its pivot point 47 and lifting the bar 58 away from the segment 36. As the segment 36 approaches its initial position, as shown for example in Fig. 4, the clamp bar 58 will engage with the latches 68, forcing the latch lever 67 about their pivot shaft 66 and when the bar 58 has ridden by the latch 68 the spring 73 will force the latches 68 into engaging position, as shown in Fig. 4.

On the under side of the cross bars 12 and 13 and adjacent to one end thereof are secured, by bolts 195, bearing members 196, which bearing members are in alignment with each other and rotatably mounted therein is a shaft 197. Secured to such shaft 197 adjacent one end thereof is a bevel gear 198 which meshes with and is driven by a bevel pinion 199 secured to the lower end of a vertically arranged shaft 200 that is rotatably mounted in bearing members 201 and 202 respectively, and formed on the inner face of the end frame member 11. Secured to the upper end of the vertically arranged shaft 200 is a bevel gear 203 which meshes with and is driven by a bevel pinion 204 secured to the power shaft 24. On the shaft 197 is secured a flanged drum or pulley 205 of any suitable dimensions. Secured to the outer face of the end frame member 10 by bolts 206 are laterally extending brackets 207, such brackets extending laterally and upwardly, as viewed in Fig. 1. Secured to the outer lower edge of each of the brackets 207, by bolts 208, are bearings 209

in alignment with each other and rotatably mounted on such bearings is a shaft 210. Secured to the shaft 210 is a flanged drum or pulley 211 of preferably the same length and diameter as the drum 205 and over the drums 211 and 205 runs an endless conveyor belt 212.

The operation of my improved machine is as follows, it being assumed that the machine has been constructed as above described and with the parts resting in their inoperative or normal position, or in the position shown for example in Figs. 4 and 6. The operator will now take a hide or skin 59a and will throw one end of the same into the space between the corrugated member 37 and the corrugated portion 59 of the clamping bar 58 so as to bring the cheeked portion of such hide or skin in front of the machine and, therefore, possibly in front of the apron 147. Having placed the hide or skin 59a, the operator will now find it necessary to depress simultaneously the knobs 70 in order that the latches 68 may be freed from the clamping bar 58. This is a safety feature of my invention which is extremely important, as it precludes the possibility of the operator starting the machine in motion until both of his hands are out of any possible danger. It is assumed, of course, that the driving belt, (not shown) has been moved by the belt shifter 27 from the loose pulley 25 onto the tight pulley 26 and that, therefore, the power shaft 24 is rotating at the proper speed and in the proper direction. Having depressed the knobs 70, the weight of the clamping bar 58 will cause the levers 48 and 49 to drop and the clamping bar 58 will move into the position shown in Fig. 7, with the rolls 52 on the arm of the bell crank lever 50 to assume the position shown in such figure and inside of the point 190 of the cam 63. As the clamp bar 58 dropped, the lug 130 on one of the levers 48 engaged with the roller 129 on the bell crank lever 127, and caused the roller 126 on the other arm of such bell crank lever 127 to engage with the cam surface 125 and rotated the latch 124 out of engagement with the latch face 120 of the latch lever 119. Simultaneously, the member 131 on the other lever 48 engaged with the portion 132 of the arm 133, which thereupon rotated the shaft 134 to move the arm 143 out of engagement with the cam 146 and moved the arm 144 into position to be engaged by the cam 145, both of these elements 146 and 145 being on the sleeve 149 that is slidably mounted on the shaft 19. Also, the rotation of the arm 133 rotated the bell crank lever 138 about the shaft 139 and caused the pins 140 in the forked end of one of the arms of the bell crank lever to engage with the sides in the annular groove 141 and force the clutch member 135 into engagement with the clutch member 34. The shaft 19 is now rotating in the direction of the arrow shown in the drawings and carrying the segment 36 therewith and

130

bringing the cheeked end of the hide or skin 59a into engagement with the cutter 107, and it is assumed that such cutter has been adjusted properly with respect to the cutter 136 5 and also that the "fanning out" devices 86 have been properly adjusted so as to fan out or smooth the hide or skin 59a just prior to the engagement of such hide or skin with the cutter 107. As the segment 36 started its rotation the roller 52 on the bell crank lever 50 passed inside of the point 190 of the cam 163 and the clamping arrangement, comprised of the levers 48 and 49, the bell crank lever 50, and link 42, remained in locked position. The 10 mechanism associated with the segment 36 is now assumed to be in the position indicated in Fig. 8 and it will be noted that the end of the hide remote from the part being operated on has dropped vertically downward and 15 alongside of the clamping bar 58. As the segment 36 continues its rotation, the lugs 193 on the levers 48 will engage with the cams 192 attached to the inner faces of the frame members 16 and 18 and the clamping device 20 above referred to will be released after the hide or skin 59a has passed beyond the cutter 107 and the clamping bar 58 will be moved away from the segment 36 or into the position shown in Fig. 9. At this point in the 25 operation, the rotation of the cam shaft 179 will, by reason of the cams 180 and 181, engaging with the rollers 187 and 188 respectively, cause a lateral movement of the movable removing roll 164 toward the stationary removing roll 150, clamping the end of the hide or skin 59a therebetween, as clearly shown in Fig. 9. As the rotation of the shaft 19 continues, the cam 146 will engage with the arm 143 and the sleeve 139 will be forced to the 30 right, as shown in Fig. 11, withdrawing the clutch member 35 from engagement with the clutch member 34 and power, therefore, will be removed from the shaft 19. As the shaft 19 approaches its full revolution, the clamp 35 bar 58 will engage with the latches 68 and also the latch 124 will engage with the latch face 120 of the latch lever 119, and such latch 40 124 will engage with the plunger 110 and all parts associated with the segment 36 will be 45 brought to rest and with the elements thereof in their normal or initial position, as indicated in Fig. 4. The removing rolls 150 and 164 will withdraw during this period the hide or skin 59a which has had the surplus or superfluous skin removed from the cheeked portion thereof and will deposit the same on the endless conveyor 212, where they will be conducted to a suitable receptacle placed at the exit end of such conveyor. The above cycle 50 of operations may be repeated indefinitely.

While I have necessarily described and illustrated the preferred embodiment of my invention somewhat in detail, it is to be understood that I may vary the size, shape, and arrangement of parts within wide limits with-

out departing from the spirit of the invention.

Having thus described my invention, what I claim as new is:

1. In an improved cheecking machine, the combination of a shaft, an arcuate support 70 for a hide mounted thereon, a clamping device associated with said arcuate support and normally held out of engagement therewith, releasing means for said clamping device for permitting the same to move into clamping engagement with the arcuate support, a power shaft, a clutch interposed between the power shaft and the first said shaft, and controlling means for said clutch operable simultaneously with the release of the clamping device. 75

2. In an improved cheecking machine, the combination of a shaft, an arcuate support for a hide mounted thereon, a hide clamping device associated therewith and normally held out of engagement therewith, a plurality of releasing means for said clamping device operable independently of each other for permitting release of the clamping device and permitting the same to move into clamping engagement with the arcuate support, a power shaft, a clutch interposed between the power shaft and the first said shaft for rotating the first said shaft in one direction only, operating means for said clutch controlled by the movement of the clamping bar into clamping position, and means associated with said clutch for disassociating the same from the power shaft and the first said shaft when said first said shaft has rotated through a single complete revolution. 95

3. In an improved cheecking machine, the combination of a shaft, an arcuate support for the hide mounted thereon, a hide clamping device associated therewith and normally held out of clamping position, a pair of releasing devices for said hide clamping device located one at either end of the machine, said releasing devices being operable independently of each other and releasing the clamping device only when both are operated, and means for rotating said shaft in one direction only. 105

4. In an improved cheecking machine, the combination of a shaft, an arcuate support for the hide mounted thereon, and rotatable therewith in one direction only, a hide clamping device associated therewith and normally held in inoperative position, releasing mechanism associated with said clamping device to permit it to move into clamping relation with the arcuate support to grip the hide or skin therebetween, a system of levers associated with said clamping device and movable into locking position when the clamping device is in clamping position, and means to maintain the system of levers in locked position during a portion of the revolution of the arcuate support. 115

5. In an improved cheecking machine, the 120

combination of a shaft, an arcuate support for a hide mounted thereon and rotatable therewith in one direction only and through a single complete revolution, a hide clamping device associated therewith and normally held in inoperative position, a system of levers associated with said clamping device and moved into locking position when the clamping device is in clamping relation with the arcuate support to clamp a hide therebetween, a cutter associated with the arcuate support for removing superfluous hide from the cheek or other portions thereof, cams associated with the system of levers and maintaining the system of levers in locked condition during the period of operative relation of the cutter with the arcuate support.

6. In an improved cheecking machine, the combination of a shaft, an arcuate support for a hide mounted thereon and rotatable therewith in one direction only, a cutter associated with said arcuate support to remove superfluous hide from a hide or skin mounted on the arcuate support, a clamping device for clamping the hide on the arcuate support, means for maintaining said clamping device normally out of engagement with the arcuate support, said means comprising a pair of elements movable independently and necessarily movable simultaneously in order to release the clamping device and permit it to move into clamping position, and means controlled by the clamping device in its movement to a clamping position for initiating rotary movement of the shaft and arcuate support.

7. In an improved cheecking machine, the combination of a shaft, an arcuate support for a hide mounted thereon and rotatable therewith in one direction only, a clamping device associated with the arcuate support, a cutter associated with said arcuate support and hide removing rollers operating in synchronism with the rotary movement of the arcuate support to remove from such arcuate support a hide that has been operated upon.

8. In an improved cheecking machine, the combination of a shaft, an arcuate support mounted thereon and rotatable therewith in one direction only, a clamping device for clamping a hide on the arcuate support, a cutter, means for maintaining the clamping device in clamped position during the engagement of a hide or skin with the cutter, and means comprising a pair of rolls for positively removing the operated-on hide from the arcuate support.

9. In an improved cheecking machine, the combination of means for removing superfluous hide from the cheecked or other portion of a hide, and a removing device comprising a roll rotatably mounted in fixed bearings, a roll rotatably mounted in movable bearings, said bearings being movable about a fixed center, and means for moving said

movable roll toward and from the fixed roll in synchronism with the movement of the superfluous hide removing means.

In testimony whereof, I have signed my name to this specification.

DANA E. HARDING.
